W. I. KIRK,
MANDOLIN TAILPIECE,
APPLICATION FILED MAY 19, 1916.

1,301,059.

Patented Apr. 15, 1919.

Inventor
Walter I. Kirk
by A. Miller Regd. U. S. Pat. Off.

UNITED STATES PATENT OFFICE.

WALTER I. KIRK, OF CHICAGO, ILLINOIS, ASSIGNOR TO LYON & HEALY, OF CHICAGO, ILLINOIS, A CORPORATION OF ILLINOIS.

MANDOLIN-TAILPIECE.

1,301,059.

Specification of Letters Patent.

Patented Apr. 15, 1919.

Application filed May 19, 1916. Serial No. 98,527.

To all whom it may concern:

Be it known that I, WALTER I. KIRK, a citizen of the United States, residing at Chicago, in the county of Cook and State of Illinois, have invented a certain new and useful Improvement in Mandolin-Tailpieces, of which the following is a full, clear, concise, and exact description, reference being had to the accompanying drawings, forming 10 a part of this specification.

My invention relates to stringed instruments, and especially to mandolins.

One of the objects of the invention is to provide an effective and advantageous construction of tail piece for a musical instrument.

Other objects of the invention will appear hereinafter.

In the accompanying drawings Figure 1 20 is a mandolin having a tail-piece embodying my present invention;

Fig. 2 is a view of the tail-piece construction of the same;

Fig. 3 is a cross section taken on line 25 3—3 in Fig. 2;

Fig. 4 is a plan view of the cover of said tail-piece.

Referring to Fig. 1, I show a stringed instrument, such for example as a mandolin, 30 having a body 1 and a finger board 2, upon which the strings 3—3 are stretched.

The connections for the lower ends of the strings 3, comprising the tail-piece of the instrument, are shown in Figs. 2 and 3. In 35 this arrangement a metal piece 17 is secured to the bottom edge 18 of the instrument as by means of screws 19. This metal piece or plate 17 has an end portion 20 extending along the top of the body 1, over which portion 20 the strings 3 are extended. Lugs 21 are punched out of the plate 17 to form hooks or abutments to engage the ends of the strings 3. The plate portion 20 is provided with transversely extending upwardly 45 projecting ribs or beads 22, over which the strings 3 pass. A supplemental plate 24 is mounted upon the plate portion 20 and also over the strings 3, the latter passing between the plates 20 and 24. The plate 24 is fastened to the plate 20 by means of straps or end portions 25 which extend down through the plate 20 and thence upwardly 50 through the same again as shown in Fig. 3. The plate 24 has a moderate amount of play 55 or movement so that it may be pressed down

toward the beads 22 to hold the strings firmly in position against the latter. A lever member 26 is arranged to press the plate 24 downward in this way, said lever member having an end or finger piece 27 and being 60 pivoted to the side flanges 28 on the plate 20 by means of pivots 29, Fig. 2. The member 26 has a laterally extending edge 30 which will act upon the plate 24 to press the same downwardly and clamp it against the strings 65 3 when said member 26 is pushed downwardly to the position shown in Fig. 3. To release the plate 24 and permit it to release the strings 3, the member 26 is swung upwardly by prying the end 27 thereof upwardly or away from the strings, so that the lateral edge 30 will be swung away from the plate 24. In this way the strings may be attached to the tail piece by forming loops 70 in their ends as shown in Fig. 2, and engaging those looped portions with the hooked members 21, and after the strings are thus attached the member 26 may be pushed downwardly so as to clamp the strings in position. When so clamped down the member 24 clamps them directly against the beads 22, thereby affording points of contact for determining the effective lengths of the strings.

A cover piece 31 is detachably mounted 85 upon the tail piece 17, said cover piece being provided with edge guide strips 32, Fig. 2, which slide upon guideways 33, at the sides of the plate 17. By sliding this cover piece 31 the strings and the member 26 with co-operating parts may be completely covered, as shown in Fig. 4, and by sliding said piece 31 the other way so as to remove it from the plate 21, the ends of the strings and member 26 will be uncovered so as to permit attachment or detachment, or other desired manipulation of the ends of the strings.

It will be understood that changes and modifications may be made without departing from the spirit of the invention.

What I claim is:

1. A stringed instrument having a tail piece comprising a plate provided with hooked members for engaging the ends of the strings, said plate being provided with beads 105 over which the strings pass, a supplemental plate having a loose connection with said tail piece, and a clamping device arranged to actuate said supplemental plate and clamp the same against the strings. 110

2. The combination of a stringed instrument and a tail piece therefor, said tail piece comprising a plate secured to the end of the instrument and provided with transversely extending beads, a supplemental plate located over the ends of the strings and loosely connected with said first-mentioned plate, and a pivoted lever having a transverse edge adapted to act against said loosely mounted plate and clamp the same against said strings.
3. The combination of a stringed instrument and a tail piece therefor, said tail piece comprising a plate secured to the end of the instrument and provided with transversely extending beads, a supplemental plate located over the ends of the strings and loosely connected with said first-mentioned plate, a pivoted lever having a transverse edge adapted to act against said loosely mounted

plate and clamp the same against said strings, and a detachable cover having a sliding connection with said plate and arranged to cover said lever.

4. A stringed instrument having a tail piece comprising a plate provided with means for engaging the ends of the strings, said plate being also provided with means for supporting the strings a small distance from the plate, a supplemental member having a loose connection with said tail piece and a clamping device arranged to actuate said supplemental member and clamp the same against the strings.

In witness whereof, I hereunto subscribe my name this 21st day of April, A. D., 1916.

WALTER I. KIRK.

Witnesses:

A. LYDA JONES,
HAZEL A. JONES.
